Attorney at Law

UNITED STATES PATENT OFFICE.

ALBERT E. HUTT, OF DETROIT, MICHIGAN.

BUSES.

Application filed June 8, 1922. Serial No. 566,757.

To all whom it may concern:

Be it known that I, ALBERT E. HUTT, a citizen of the United States of America, residing at Detroit, in the county of Wayne and State of Michigan, have invented certain new and useful Improvements in Busses, of which the following is a specification, reference being had therein to the accompanying drawings.

10. This invention relates to motor busses and especially to a means for partially enclosing the top deck of such busses. The use of automobile motor busses in the larger cities of this country is becoming increasingly 15 popular with the improvement in street paving. The majority of busses at present in common use have an upper deck usually capable of seating as many passengers as can be accommodated in the lower portion of 20 the bus.

In fair weather and especially during the summer months, the upper deck is considered more desirable than the interior of the bus because of the better view afforded to 25 passengers when seated at a greater height.

In chilly or rainy weather it is usually disagreeable to ride upon the upper deck because of the absence of any protection from wind or rain and the carrying capacity of 30 the bus is thereby substantially cut in half because the majority of passengers will not ride upon the upper deck and suffer the consequent exposure.

The principal object of my present invention is to provide permanent, continuous outer roof members over each row of seats on the upper deck, there being a central aisle between said rows of seats, and each of said permanent roof sections extending laterally 40 inwardly from the outer upper deck walls of the vehicle and terminating about on a line with the inner ends of said seats, so that a longitudinal roof opening or passage way, in vertical alignment, with the center aisle 45 and of about the same width as the latter, is afforded between the inner juxtaposed edges of said permanent roof sections, which latter are of a height greater than the height of a seated passenger, and less than the average 50 height of a standing passenger, the edges of said roof sections being about breast high for an average passenger and affording ample protection for the upper deck seated passengers, and convenient guiding or 55 steadyng means for the upper deck stand-

ing passengers, as they move about in the center upper aisle, the head of the average upper deck passenger standing in the center aisle projecting above said roof sections.

A further object of the invention is to 60 provide a protection for the seats of the upper deck which shall permit ready access to any of the seats without materially increasing the height of the bus, because there are many places in cities beneath which there 65 is very little more room than is necessary to permit the passage of a bus when passengers are seated upon the upper deck.

In the drawings, Figure 1 is a perspective view of a preferred form of the invention showing the protecting covering in place; 70

Fig. 2 is a perspective view showing the upper portion of the bus as it appears from one side of the rear end, the point of view 75 being a little way above the top of the bus;

Fig. 3 is a vertical transverse section of the upper deck with the covering in place;

Fig. 4 is an enlarged sectional detail of a portion of Fig. 3; 80

Fig. 5 is a fragmentary top plan view taken at one edge of the top;

Fig. 6 is a horizontal section taken on the line VI—VI of Fig. 4; 85

Fig. 7 is a vertical transverse section similar to Fig. 3, showing a modified form of construction;

Fig. 8 is a horizontal section taken on the line VIII—VIII of Fig. 7, and

Fig. 9 is a fragmentary elevation looking 90 from the interior in the direction indicated by the arrow IX in Fig. 7.

Extending upward from the rear platform 1 of the motor bus illustrated in the drawings, is a rear stairway 2 having a hand rail 3. In the embodiment illustrated this stairway has its upper end at the left side of the top deck of the bus. The seats 4 having backs 5 are arranged along both sides of the upper deck, a space being left between the adjacent ends of the seats to form a center aisle as shown in Figs. 3 and 7. Each seat usually accommodates two passengers. The floor of the upper deck is usually slatted, the spaces between the slats extending to the edges of the deck as indicated at 6 in Fig. 1 so that rain falling upon the upper deck may be discharged at the sides. 100

A sheathing strip 7, preferably of sheet metal extends from about the level of the 110

seat 4 downward to within four or five inches of the deck, the lower edge being secured to a longitudinal bar 8 supported by brackets 9.

5 A cloth strip 10, the upper edge of which is secured beneath a cleat 11, extends downward from the lower edge of the sheathing 7 substantially to the deck level to close the space beneath the lower edge of the sheathing 7.

A support 12 preferably consisting of a metal tube having its ends flattened at 13 and 14 is mounted at opposite ends of each seat, the end 13 being bolted to the bar 8 15 and the end 14 being bolted to the upper end of a leg 15 which is secured to the deck by a bracket 16. The support is substantially U-shaped with the upright portions substantially vertical and the connecting 20 portion 17 substantially horizontal, the horizontal portion being connected with the vertical portions by bends 18 and 19.

A series of slats 20 preferably of wood are secured upon the portions 17 and 18 of the 25 supports 12 as by screws 21, and upon these supports is placed a roof fabric 22 of any suitable waterproof material.

From the foregoing description, it will be apparent from Figures 2, 3 and 7, that the 30 upper deck is provided with two laterally, inwardly extending, permanent, continuous roof members, which extend from the front to the rear of the bus and have a longitudinal opening therebetween, which is in about 35 vertical alignment with the center aisle and about the same width as the latter, said inwardly extending, permanent, continuous roof members being in practice about breast high to a passenger of average height so that 40 his head when standing in the outer aisle projects above said roof sections, and the standing upper deck passenger can steady himself from the lurching of the bus when in motion by grasping the edges of these roof 45 sections with his hands as he walks in the upper center aisle towards the front or back of the bus.

It will thus be seen that my novel upper 50 deck structure comprises seats on opposite sides of a central upper deck aisle, permanent, continuous roof structures above said seats, but not above said aisle, having a longitudinal fore and aft opening and if desired suitable means can be employed for closing 55 the openings under the roof structures constructed as aforesaid so as to exclude rain, snow, sleet and the like.

I have however found in practice, that 60 with my invention of the permanent roof sections, wherein the longitudinal central opening is provided in the upper deck, the severest winds are only slightly felt by any of the passengers on the upper deck and that very little rain reaches any passengers and 65 none at all those passengers that are occupy-

ing the seats next to the outside of the vehicle.

Furthermore, with the sliding curtains or blinds that I provide on the aisle side of the permanent continuous upper deck covering, 70 all the passengers on the upper deck are protected entirely from rain, snow, sleet or the like.

It will thus be seen that my novel permanent, continuous upper deck roof structure 75 having the longitudinal central opening therein, affords protection to the seated upper deck passenger from the hot sun in summer time, without detracting from the ventilating or open air feature, which is so 80 desirable and the sides can be closed either separately or jointly at the will of the passengers and as their necessity and comfort dictate, and in addition the removal of the central longitudinal portion of the upper 85 deck effects a reduction in the weight of the bus, which is desirable, as is evident.

A substantially triangular strip of wood 23 is arranged along the inner edge of the roof fabric to prevent rain from flowing off 90 the aisle side of the roof. As shown in Fig. 2, a similar strip 24 forming an extension of one of the strips 23 is located at the end of the roof adjacent to the head of the stairway. The outer edge of the roof fabric 22 95 has a downwardly extending flap 25 secured thereto preferably by a seam.

At about the height of the top of the backs 5 of the seats is a rail 26 which extends at substantially uniform height almost completely around the top portion of the bus. 100 As shown in Fig. 2 one end of the rail 26 is substantially a continuation of the hand rail 3 of the stairway 2 which, as before stated, has its upper end at the left hand side 105 of the bus. From this rail 3, the rail 26 extends to the forward end of the bus, thence across the front, back along the right hand side and across the rear of the bus, curving at the corners and terminating adjacent to the right hand side of the landing at the top 110 of the stairway.

Between the rail 26 and the sheathing 7 is a protecting metallic network strip 27 shown in Figs. 2 and 3. 115

In fair weather the parts thus far described constitute the protection for the upper portion of the deck but when additional protection is needed because of rain or cold winds, removable curtains may be 120 secured to cover the open spaces. The upper curtain member 28 consists of any suitable waterproof fabric such as imitation leather or oil cloth, preferably of the same material as that used for the roof. The upper edge 125 of this curtain is secured by any suitable fastening means 30 such as the spring snap fasteners and studs commonly used for automobile curtains, beneath the flap 25 and thence it extends downward inside the rail 130

26 and underneath the rail to the outside of the network strip 27 and the outside of another curtain 29 where it engages other similar fastening means to hold the lower edge securely in place. The curtain 29 is secured at its upper edge beneath the lower edge of the curtain 28 and its lower edge extends downward beyond the lower edge of the network 27 where it is secured by 10 similar fasteners 30.

The curtains 28 and 29 may be made in sections of any suitable length but the most convenient arrangement is believed to be that illustrated in Figs. 1 and 2 in which 15 the curtain 28 extends from a front central window 31 along the entire length of the top of the bus and around the corner to the rear. The curtain on the left hand side extends from the window 31 the entire length of the 20 left hand side to the back of the last seat on the left side of the top deck. A curtain 32 extends across the entire width of the rear seat on the left hand side from the roof to the top of the seat back 5. Within the 25 upper curtain 28 are secured a series of panels 33 of celluloid, glass, or other transparent material. As shown in Fig. 1, the curtain 29 has a section 34 extending across the front of the bus top and a side section 35 extending from the section 34 the full length of the bus and around the rear end on the right side with a similar section on the left side extending from the front section for the full length of the left side to the end of the 30 network panel 27 adjacent to the head of the stairway.

When the curtains are secured in place, the sides, front and rear of the top of the bus are substantially completely enclosed with the exception of the space leading from the landing at the head of the stairway to the aisle between the seats and this protection will be entirely sufficient in the absence of rain or snow, but as an additional protection, curtains 35 may be provided as illustrated in Figs. 4, 5 and 6 to extend from the edge of the roof on the side next to the aisle, downward between the supports 12, channels 36 being secured upon the supports to guide 45 the edges of the curtains and to prevent the rain from beating in at the edges. A spring roller 37 is provided for each curtain 35 and a hood 38 is arranged adjacent to the strip 23 as a protection for the roller and 50 for the joint between the curtain and the edge of the roof. The channels may obviously be extended downward as far as desired.

A modified form of construction is illustrated in Figs. 7, 8 and 9 in which sashes 39 are arranged within pockets 40 formed between inner and outer panels 41 and 42, which take the place of the sheathing 7 and the network strip 27. In bad weather 65 the sashes 39 may be elevated into the posi-

tion shown in Fig. 9 to close the opening between the top of the panel 42 and the roof 22.

The roof 22 will be very little higher from the upper deck of the bus than the heads of 70 the passengers so that the additional height added to the bus by this construction will not interfere with its use under elevated roads, viaducts, bridges and other structures extending across the roadway where 75 such busses operate. When a passenger stands erect in the aisle between the seats, his head will be above the top of the roof, but when seated there will be plenty of head room beneath the protecting top. A door 43, 80 may be placed in the aisle to assist in closing the top.

It will be apparent that there is provided a device of the character described, possessing the particular features of advantage 85 enumerated as desirable, but which obviously is susceptible of modification in form, proportion, details of construction and arrangement of parts without departure from the principle involved or sacrificing any of 90 its advantages. It is therefore to be understood that the invention is not limited to the specific details shown but that the means and construction herein disclosed are merely 95 illustrative and the invention is therefore claimed in any of its forms or modifications within the legitimate and valid scope of the appended claims.

I claim:—

1. In a device of the character stated, a 100 passenger carrying vehicle, having an upper deck provided with seats at opposite sides thereof, separated by a central aisle and laterally extending permanent, continuous upper deck roof sections projecting inwardly 105 from the outer upper deck walls over said seats, and provided with a longitudinal opening in vertical alignment with and of about the same width as said central aisle extending from the front to the rear of said roof 110 sections, the height of said roof sections from the upper deck floor being greater than the height of the seated passenger and less than the height of the average standing passenger, so that the head of the latter projects above 115 said roof sections when standing in said central aisle.

2. In a passenger carrying vehicle, an upper deck, provided with transversely arranged seats at opposite sides thereof separated by a central aisle, laterally extending permanent continuous roof sections above said seats and projecting inwardly from the outer upper deck walls, and provided with a central longitudinal opening extending 125 from the front to the rear of said roof sections, the height of said roof sections from the upper deck floor being greater than the height of the seated passengers and less than the height of the average passenger standing 130

in said center aisle, so that the head of the latter projects above said roof sections when standing, and movable curtains arranged at the ends of said seats adjacent to said central aisle.

3. In a passenger carrying vehicle, provided with a central aisle and an upper deck with seats upon said deck arranged transversely on opposite sides of said central aisle,

10 means for protecting said seats, comprising permanent continuous roof structures extending from the outer walls of said upper deck over said seats only, the height of said roof sections from the upper deck floor being

15 greater than the height of the seated passengers and less than the height of the average passenger standing in said central aisle and having their juxtaposed inner edges separated by a central longitudinal passage ex-

20 tending from the front to the rear of said vehicle, in vertical alignment with said central aisle and of substantially the same width as the latter, suitable closures between tops of walls and outer edges of the roof sections,

25 upright supports for the inner edges of said permanent, continuous roof sections, and movable curtains arranged at the ends of said seats adjacent to said central aisle.

4. In a passenger carrying vehicle, an up-

per deck having a central aisle, and permanent, continuous upper deck roof sections, extending laterally inwardly from the outer upper deck walls, and fixedly secured thereto, the inner juxtaposed edges of said continuous, permanent roof sections being separated by a central longitudinal opening extending from the front to the rear of the vehicle in alignment with said central aisle and of substantially the same width as the latter, the height of said roof sections from the upper deck floor, being greater than the height of the seated passengers and less than the height of the average passenger standing in said central aisle and a row of transverse seats positioned on each side of said central aisle under each of said permanent, continuous upper deck roof sections, the inboard ends of said seats terminating in proximity to said aisle, and the outboard ends terminating in proximity to said outer upper deck walls.

In testimony whereof I affix my signature in presence of two witnesses.

ALBERT E. HUTT.
